Specification for Design.

Patented Oct. 4, 1921.

Application filed March 29, 1921. Serial No. 456,631. Term of patent 7 years.

To all whom it may concern:

Be it known that I, ARTHUR L. BREITENSTEIN, a citizen of the United States, residing at 812 Ardmore avenue, Akron, Summit county, Ohio, have invented a new, original, and ornamental Design for a Tire-Tread, of which the following is a specification, reference being had to the accompanying drawings, forming a part thereof.

In the drawings, Figure 1 is a plan view of a tire embodying my new design, and Fig. 2 is a section taken on the line 2—2, Fig. 1.

I claim:
The ornamental design for a tire tread substantially as shown.

ARTHUR L. BREITENSTEIN.
